UNITED STATES PATENT OFFICE

2,638,200

LOADING MACHINE

John D. Russell, Cranberry Township, Venango County, Pa., assignor to Joy Manufacturing Company, a corporation of Pennsylvania

Application June 11, 1945, Serial No. 598,731

5 Claims. (Cl. 198—10)

1

This invention relates to mechanical loading machines and, more particularly, to improvements in mobile loaders of the type used extensively in underground mining operations.

The principal object of this invention is to provide a mobile loader for use in underground mine chambers, which is highly and readily maneuverable and capable of loading minerals along the ribs of the mine chambers, in the corners and other usually inaccessible places, and of delivering the same to a vehicle traveling in the mine chambers in either a fixed or variable path for transportation to the surface. This is accomplished by supporting the loader on two sets of independently steerable, rubber-tired wheels and mounting the gathering head on one of the axles of the car for lateral swinging movement therewith so that the head may be readily swung to either side of the car. This construction will permit the loader to be moved in a straight line when the wheels are in line with the chassis; in an arcuate path when one set of wheels are turned and the other held in line with the chassis, or both sets are turned in opposite directions; and in a substantially sidewise direction, that is, a diagonal or an oblique direction, when both sets of wheels are turned in the same direction, thereby making it possible to maneuver readily the loader into position to reach and load the minerals in the most inaccessible portions of the mine chamber.

Another object of this invention is to provide a mobile loader which is of novel construction and design, is easy to operate, and is of such rugged and sturdy construction as will enable it to perform readily the task of loading minerals in underground mining.

These and other objects, which will hereinafter be made apparent to those skilled in this particular art, are accomplished by means of this invention, one embodiment of which is described in the following specification and illustrated in the accompanying drawings, wherein:

Fig. 1 is a top plan view of a loading machine, made in accordance with my invention;

Fig. 2 is a side elevation of my improved loader;

Fig. 3 is an enlarged sectional view of the gathering head and forward end of the chassis, taken on the longitudinal axis of the loader;

Fig. 4 is an enlarged plan view of the gathering head, having portions thereof broken away for convenience of illustration;

Fig. 5 is an enlarged sectional view, taken on line V—V of Fig. 2;

Fig. 6 is a sectional view, taken on line VI—VI of Fig. 5;

2

Fig. 7 is a sectional view, taken on the broken line VII—VII of Fig. 4 and having certain parts removed to illustrate better my invention;

Fig. 8 is an enlarged sectional view of the drive for the conveyor and hydraulic system of the loader;

Fig. 9 is a sectional view taken on line IX—IX of Fig. 8.

Referring now to the drawings in detail, 10 represents, in its entirety, a loading machine, made in accordance with the present invention, having a chassis 11 of fabricated construction, which is supported by a set of steerable wheels 12 and a set of drive wheels 13.

15 The wheels 12 are mounted on a wheel supporting device 14, preferably of the construction and type set forth in U. S. Letters Patent No. 2,301,144, issued to me on November 3, 1942, carried by the chassis 11. Each of the wheel mounting devices 14 is mounted on the chassis 11 for turning movement and each is connected by a tie rod 15 with a piston rod 16 operating in a cylinder 17, mounted transversely of the chassis. As the piston rods 16 move in unison to either side, it is apparent that the wheels 12 will be turned to steer the loader.

20 The drive wheels 13 are journaled on the wheel receiving portions of a drop axle 18, which extends underneath and supports the forward end of the chassis 11. The axle 18 has an enlarged central portion 19, carrying a bearing 20, which engages a pin 21, mounted in the chassis 11 to provide an antifriction joint between the axle and the chassis and permit the axle to turn readily in a horizontal plane relative to the chassis.

25 To strengthen and reinforce the axle 18, a member 22, which extends through the chassis 11, is bolted to each side thereof and has an enlarged centrally bored portion 23 for receiving a pin 24, journaled in a bearing 25, carried by the upper part of the chassis 11.

30 The member 22 and the axle 18 form a double or split axle for the car and, since two relatively short, vertically spaced pins are used to pivot the axle on the car, a sturdier construction is obtained than would be possible with the use of a single pin and the turning movement of the axle in a vertical plane is effectively resisted, while turning in a horizontal plane is freely permitted, thereby providing additional steering capacity for the loader by the turning of the drive wheels 13.

35 Turning of the axle member 18—22 is accomplished by hydraulic jacks 26, mounted on the sides of the chassis 11, each of which has its piston rod 27 connected to the axle 18. The jacks 26 are preferably of the single action type and are so interconnected that, as pressure is applied

to one jack, the other will be connected to the exhaust. Thus, by adjusting the size of the exhaust port in the jacks, the speed of turning the axle 18-22, by the admitting and exhausting of fluid to and from the jacks, can be readily controlled.

Journaled on the axle 18, for swinging movement in a vertical plane, are the side members 30 of a gathering head 31 of fabricated construction, which is adapted to be swung laterally as the axle is turned.

In order to support the head 31 during its entire range of lateral movement, the chassis 11 has an arcuate track 32 at its forward or front end, upon the top and bottom of which are ride rollers 33-34, carried by a frame 35, extending transversely of the chassis. A hydraulically operated single acting jack 36 is mounted on each end of the frame 35 and the piston rods 37 of the jacks are pivotally connected to the head 31. Thus, as the axle 18-22 is turned, the head 31 is not only supported during its lateral swinging movement by the construction above described, but by controlling the admission of fluid pressure to the jacks 36, the elevation of the head may also be adjusted at any and all positions of its lateral movement.

The gathering head carries a pair of gathering arms 40, which are adapted to gather the mineral being mined from the floor of the mine chamber and place the same on an endless chain and flight conveyor 41, carried by the head for delivery to an endless chain and flight conveyor 42, carried by the chassis 11, which conveys the mineral to a haulage unit for transportation from the mine chamber.

The drive wheels 13, the gathering arms 40 and the conveyor 41 are all driven by motors 44, carried by the head 31 and in substantially the same manner as set forth and described in U. S. Letters Patent No. 2,360,232, John D. Russell, issued October 10, 1944, and, since the specific details of the drive forms no part of the present invention, it will suffice to point out that the wheels 13 may be driven in either direction from shafts 46, having oppositely rotating clutch members 47-48 mounted thereon, which are driven by the motors 44 and selectively connected to the shafts by a sliding clutch engaging member 49. Power is delivered to the wheels through chains 50 and sprockets 51-52 attached to the shafts 46 and the wheels 13 respectively.

Each motor 44 also drives clutch members 53, which may be selectively connected by sliding clutch members 54 to shafts 55, geared to a foot-shaft 56, journaled in the head 31. The shaft 56 carries sprockets 57 for driving the conveyor 41 and pinions 58 for driving the crank arms 59, which support the gathering arms 40.

The conveyor 42 travels over a conveyor pan 60, carried by the chassis 11, around idler sprockets 61-62, at each end thereof. The inactive reach of the conveyor travels underneath the pan 60 where it passes between the axle 13 and member 22 and is driven by a drive sprocket 63, secured to a shaft 64, journaled in the chassis 11. Shaft 64 is driven through a worm gear 65 and worm 66 from a shaft 67, having a clutch element 68, thereon, for connecting the shaft to a shaft 69 through the clutch element 70, which is adapted to be moved into engagement with the clutch element 68. Shaft 69 is driven by motor 71 through gear 72 and motor pinion 73. The motor 71 also drives a pump 74, which draws fluid from the tank 75 and pumps it to the vari-

ous hydraulic jacks, previously described. The admission of fluid pressure to the jacks is controlled by suitable control valves 76, mounted on the side of the loader adjacent an operator's platform 77.

From the foregoing description, it is apparent that I have produced a loader for underground use which is capable of being readily maneuvered into position to load all the minerals in the producing area of the mine, since the drive wheels 13 may be turned, independently of the steering wheels 12, by admitting fluid pressure to one or the other of the jacks 26, to swing the gathering head 31 laterally to one side or the other of the loader.

Further, since both sets of wheels 12 and 13 are capable of independent turning movement, the loader can be driven either forward or rearward in a straight path, when both sets of wheels are set to travel in a path parallel to the major axis of the machine. It will turn corners when either set of wheels is turned and the other set held parallel to the longitudinal axis, and, when both sets of wheels are turned in opposite directions, the radius of the turning movement of the loader will be materially reduced. When the two sets of wheels are turned in the same direction, however, the loader will travel in an oblique or diagonal path and move bodily in a generally sidewise direction. Thus, any desired path of travel can be selected by the operator of my improved loader, giving it such a high degree of flexibility as will readily permit the loader to be maneuvered to any desired location in the mine without danger of getting it in a position where it is unable to extricate itself as frequently happens, for example, when a standard four-wheel steerable mine vehicle gets too close to a rib or the like and has to be pulled away before it can continue to be operated.

While I have explained and described one embodiment of my invention, it is to be understood, that, within the scope of the appended claims, the invention may be practiced otherwise than as specifically illustrated and described.

What I claim as new and desire to secure by Letters Patent is:

1. In a loading machine, the combination of a chassis, an axle pivoted to said chassis for supporting the forward end thereof, drive wheels journaled on said axle, a gathering device, carried by said axle and adapted to swing laterally on the turning of said axle, steerable wheels supporting the rear of said chassis, means for turning said axle, and means for turning said steerable wheels.

2. The combination of the character set forth in claim 1, in which an endless conveyor passes over the chassis and the axle is split to permit one reach of the conveyor to pass between the upper and lower sections thereof.

3. A loading machine of the character set forth in claim 1, in which the chassis has an arcuate track at the forward end thereof, and the gathering device is supported on a frame, having rollers traveling on said track.

4. A loading machine of the character set forth in claim 1, in which the gathering device is pivoted on the axle for movement in a vertical plane and the chassis has a track at the forward end for supporting the end of an extensible member, employed in swinging the gathering device in such plane.

5. A loading machine of the character set

forth in claim 1, in which means are provided for driving the drive wheels in one direction at a relatively high speed, and in the opposite direction at a relatively slow speed.

JOHN D. RUSSELL. 5
